US00D925583S

(12) **United States Design Patent** (10) Patent No.: **US D925,583 S**
(45) Date of Patent: **** Jul. 20, 2021**

(54) **DISPLAY SCREEN OR PORTION THEREOF
WITH GRAPHICAL USER INTERFACE**(71) Applicant: **Apple Inc.**, Cupertino, CA (US)(72) Inventors: **Patrick Lee Coffman**, San Francisco, CA (US); **Raymond Sepulveda**, San Jose, CA (US)(73) Assignee: **Apple Inc.**, Cupertino, CA (US)(***) Term: **15 Years**(21) Appl. No.: **29/757,035**(22) Filed: **Nov. 2, 2020****Related U.S. Application Data**

(63) Continuation of application No. 29/723,756, filed on Feb. 10, 2020, now Pat. No. Des. 901,533, which is a continuation of application No. 29/692,223, filed on May 23, 2019, now Pat. No. Des. 875,127, which is a continuation of application No. 29/675,561, filed on Jan. 3, 2019, now Pat. No. Des. 854,574, which is a continuation of application No. 29/646,535, filed on May 4, 2018, now Pat. No. Des. 841,685, which is a continuation of application No. 29/582,383, filed on Oct. 27, 2016, now Pat. No. Des. 820,304.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines illustrate a display screen or portion thereof, and form no part of the claimed

design. The dotted broken lines illustrate a boundary which forms no part of the claimed design and the faded portion within the dotted broken lines forms no part of the claimed design.
